UNITED STATES PATENT OFFICE.

FREDERICK B. A. KIRSTEN, OF BALWYN, MELBOURNE, VICTORIA, AUSTRALIA.

LOOSE-LEAF BOOK OR BINDER.

Application filed March 21, 1922. Serial No. 545,404.

To all whom it may concern:

Be it known that I, FREDERICK BENJAMIN ADOLPH KIRSTEN, a subject of the King of Great Britain and Ireland, and a resident of 5 the postal district of Balwyn, a suburb of the city of Melbourne, in the county of Bourke, State of Victoria, Commonwealth of Australia (whose post-office address is "Khama," Kireep Road, in the said postal district of 10 Balwyn), have invented certain new and useful Improvements in Loose-Leaf Books or Binders, of which the following is a specification.

This invention relates to loose leaf books 15 or binders of the type in which the two halves or sections of the book cover are united by flexible binding thongs or tapes upon which one of the cover sections is adapted to slide in relation to the other 20 section.

The object of the present invention is to provide an improved mechanism of simple and inexpensive construction for exerting a powerful tension upon said thongs whereby 25 the two cover sections are drawn tightly together upon the leaves and are locked in such tightened position so that accidental displacement or unauthorized removal of the leaves is effectively prevented.

30 Referring to the drawings which form part of this specification:—

Figure 1 is a view looking at the interior of the slidable cover section of a loose leaf book or binder showing the invention applied thereto. Portions are broken away for convenience of illustration.

Figure 2 is a view looking at part of the inner face of the slidable cover section showing the apertures through which the invention 40 is operated.

Figure 3 is a section taken on line A—A of Figure 1.

Figure 4 is a section on line B—B of Figure 1.

45 Figure 5 is a detail view showing the pivotal connection of the guide piece to the tightening lever, the sliding grip being removed for convenience of illustration.

Figure 6 is an enlarged section taken longitudinally through the fastening thong showing the manner in which the latter is secured to the guide piece by the sliding grip.

50 Figure 7 is a section on line C—C of Figure 6.

Figure 8 is an end view of the sliding grip showing the teeth or serrations thereon.

According to the invention, one end of a tightening lever 2 is pivoted at 3 to the slidable cover section 4 this lever being provided near its other end with an upstanding finger piece 6 by which the lever is operated to exert tension upon the binding thongs and thus draw the cover sections tightly together on the leaves as aforesaid.

Pivoted at 7 to said tightening lever is a guide piece 8 through which passes the usual single fastening thong or tape 9 which is connected at its inner end to the centre of a cross bar 11 uniting the various binding thongs 12 which extend between the cover sections and through the openings or gullets in the leaves. These binding thongs 12 are secured at their outer ends to the other cover section 13 in the usual manner. The pivoted 75 guide piece 8 may be conveniently formed of a flat plate the opposite side edges of which are inturned as at 14 to form a guide-way through which the thong 9 passes.

Also accommodated by said guide piece 80 is a sliding grip 16 which is adapted to engage and grip the thong passing through the guide piece thereby securing said thong to the guide piece and the tightening lever 2 so that when the latter is operated in one 85 direction tension is exerted on the thongs to contract the cover sections on the leaves whilst reverse movement of the lever causes such tension to be relaxed.

The sliding grip referred to is provided at 90 one end with teeth or serrations 17 adapted to be embedded in the thong 9 and adjacent this toothed or serrated edge the grip has an inclined portion 18 which is adapted to engage the inturned portions 14 of the guide 95 piece and thus force the teeth or serrations 17 into the thong when the grip is moved in one direction whilst movement of the grip in the opposite direction causes the thong to be released. The opposite end of the sliding 100 grip has an upstanding lug or finger portion 19 by which the grip is pulled through the guide piece to force the teeth or serrations into the thong as aforesaid.

Carried by the tightening lever is a depending catch 21 which is adapted to engage in holes or depressions 22 in a base plate 23 attached to the slidable cover section 4. These holes or depressions are arranged in the form of a segment or arc struck from 110

the pivotal point of the lever as in Figure 1 so that when the lever 2 is drawn to the left in Figure 1 to tighten the thongs the catch 21 slips into an appropriate hole 22 and thus effectively retains the lever and thong in tightened position. Said catch is preferably of hooked or like shape as in Figure 4 being thus provided with an inclined face on one side so that it will rise out of the hole or depression when the lever is moved in one direction (to the left in Figures 1 and 4) but is firmly held in said hole by the tension of the thongs on the lever in the opposite direction.

15 The outer or free end of the tightening lever preferably carries a locking piece or extension 24 of segmental form. This locking piece may be formed integral with or attached to the tightening lever and is adapted to engage the sliding bolt or latch 26 of a key actuated lock 27 which is attached to the slidable cover section so that when the key is turned in the lock the sliding bolt or latch thereof passes over said locking piece or extension as in Figures 1 and 3 and thus prevents the tightening lever being raised to release its catch from the hole or depression 22 in which it is engaged as above mentioned. Unauthorized manipulation of the lever and removal of the leaves may thus be prevented.

30 The apparatus above described may be hidden from view within the slidable cover section, the inner face or wall of the latter being provided with apertures 29 in appropriate positions to pass the finger pieces on the tightening lever and the sliding grip and thus permit of manipulation thereof and to enable the key to be inserted in the 40 lock.

To separate the cover sections for removal of the leaves it is merely necessary to release the catch of the tightening lever by moving the latter slightly in an outward direction or to the left in Figure 1 so that the catch 21 is lifted out of the hole or depression 22 in which it is engaged. The lever may be now moved inwardly or to the right in Figure 1 so that the tension on the thongs is relaxed. By moving the sliding grip 16 outwardly in the pivoted guide piece the fastening thong 9 passing therethrough may be thus freed from the teeth or serrations of the grip and the cover sections drawn apart to the desired extent.

45 When it is desired to contract and lock the cover sections upon the leaves the outer end of the fastening thong 9 passing through the guide piece is first pulled to draw the cover sections upon the leaves as tightly as possible by hand. The sliding grip is then moved to embed its teeth or serrations in said thong and thus fasten the latter to the guide piece. The tightening lever is now 55 swung outwardly over the segmentally ar-

ranged holes or depressions in the base plate and owing to the pivotal attachment of the guide piece to the lever the arcuate movement of the latter is converted into a straight and direct pull on the thongs. When sufficient 70 tension has been thus exerted on the thongs the catch of the lever is engaged in one of the holes or depressions 22 thereby holding the cover sections firmly and tightly upon the leaves. The key may be then turned in 75 the lock 27 to prevent unauthorized operation of the lever and removal of the leaves as aforesaid.

By the invention a simple, inexpensive and highly efficient means of tightening and 80 locking the two cover sections upon the leaves is provided. Any desired leverage and tension being obtainable to accord with the size of the book or other requirements, by varying the length of the tightening 85 lever and the relative positions of its pivot and the pivotal point of the guide piece thereon. It will be evident that said lever may be of any desired shape, such for instance as a disc or segment of a circle, with 90 equivalent results.

Furthermore, it is to be understood that the grip and other parts of the device may be altered or modified in various respects without departing from the spirit and scope 95 of the invention which resides primarily in the means whereby the swinging or pivotal movement of the tightening lever is converted into a straight or linear pull on the thongs.

100 Having now described my invention what I claim as new and desire to secure by Letters Patent is:—

1. In a loose leaf book or binder of the kind wherein the cover sections are united 105 by flexible binding thongs or tapes the combination with a fastening thong connected to the binding thongs upon one of the cover sections, a tightening lever mounted on said last named cover section, a guide piece pivoted to the tightening lever and slidably 110 accommodating the fastening thong and means to grip said fastening thong upon said guide piece for the purpose set forth.

2. In a loose leaf book or binder of the 115 kind wherein the cover sections are united by flexible binding thongs or tapes the combination with a fastening thong connected to the binding thongs upon one of the cover sections, of a tightening lever mounted on 120 said last named cover section, a guide piece pivoted to the tightening lever, said fastening thong passing through the guide piece, and a sliding grip accommodated by the guide piece and adapted to grip the fastening thong when moved in the opposite 125 direction on the guide piece, for the purpose set forth.

3. In a loose leaf book or binder of the kind wherein the cover sections are united 130

by flexible binding thongs or tapes, the combination with a fastening thong connected to the binding thongs upon one of the cover sections, of a tightening lever mounted on 5 said last named cover section, a guide piece pivoted to the tightening lever and slidably accommodating the fastening thong and a sliding grip accommodated by the guide piece and having teeth or serrations at one 10 end, an inclined portion adjacent said serrations and an upstanding lug or finger portion at its other end whereby the teeth or serrations are forced into the fastening thong by engagement of said inclined portion with the guide piece substantially as 15 described.

4. In a loose leaf book or binder of the kind wherein the cover sections are united by flexible binding thongs or tapes, the 20 combination with a fastening thong connected to the binding thongs upon one of the cover sections, of a tightening lever mounted on said last-named cover section, a guide piece pivoted to said lever and having 25 overturned side edges adapted to form a guideway for the fastening thong and a sliding grip accommodated by said guideway and adapted to grip the fastening thong upon the guide piece for the purpose set 30 forth.

5. In a loose leaf book or binder of the kind wherein the cover sections are united by flexible binding thongs or tapes, means 35 for exerting tension on said thongs to contract the cover sections upon the leaves, comprising a tightening lever, a pivotal connection between said lever and one of the thongs whereby the swinging or pivotal movement of the tightening lever is converted into a straight or linear pull on the 40 thongs, and a catch carried by the tightening lever and adapted to engage holes or depressions in a relatively stationary part to lock said lever in different angular positions for the purpose set forth.

6. In a loose leaf book or binder of the kind wherein the cover sections are united by flexible binding thongs or tapes, means 45 for exerting tension upon said thongs to contract the cover sections upon the leaves, comprising a tightening lever, means pivoted to said lever to grip one of the thongs and a catch carried by said lever and adapted to engage holes or depressions in an adjacent member whereby the lever is locked 50 in different angular positions, said catch being hooked or inclined so as to rise out of said holes or depressions when the lever is moved in one direction and to be firmly retained in such holes or depressions by the 55 tension of the thongs on the lever in the opposite direction.

7. In a loose leaf book or binder of the kind wherein the cover sections are united 60 by flexible binding thongs or tapes, means

for exerting tension on said thongs to contract the cover sections upon the leaves comprising a tightening lever on one of the cover sections, a pivotal connection between said lever and one of the thongs, a base 70 plate secured to said last-named cover section, said base plate having a series of segmentally arranged holes or depressions therein and a catch carried by the tightening lever and adapted to engage said holes or depressions to lock the tightening lever in different angular positions.

8. In a loose leaf book or binder of the kind wherein the cover sections are united by flexible binding thongs or tapes, means 80 for exerting tension on said thongs to contract the cover sections upon the leaves, comprising a tightening lever, a pivotal connection between said lever and one of the thongs whereby the swinging or pivotal movement of the tightening lever is converted into a straight or linear pull on the 85 thongs and an upstanding lug or finger piece on the tightening lever near its outer end for the purpose set forth.

9. In a loose leaf book or binder of the kind wherein the cover sections are united by flexible binding thongs or tapes, means 90 for exerting tension on said thongs to contract the cover sections upon the leaves, comprising a tightening lever, a pivotal connection between said lever and one of the thongs whereby the swinging or pivotal movement of the tightening lever is converted into a straight or linear pull on the 95 thongs, a segmental locking piece or extension carried by the outer end of the tightening lever and a lock arranged adjacent said extension whereby the latch or bolt of the lock is adapted to engage the extension 100 to prevent unauthorized manipulation of the tightening lever.

10. In a loose leaf book or binder of the type wherein the cover sections are united by flexible binding thongs or tapes on which 110 one of the cover sections slides, the combination with a fastening thong connected to said binding thongs in the slidable cover section, of a tightening lever pivoted on said slidable cover section, means to retain 115 said lever in different angular positions about its pivot and a thong gripping device pivoted to said lever whereby the fastening thong may be secured to or released from the tightening lever for the purpose 120 specified.

11. In a loose leaf book or binder of the type wherein the cover sections are united by flexible binding thongs or tapes on which 125 one of the cover sections slides, the combination with a fastening thong connected to said binding thongs in the slid- able cover section of a tightening lever piv- oted on said slidable cover section, means carried by said lever to grip the fastening 130

thong, a catch carried by said lever and adapted to engage segmentally arranged holes or depressions in a base plate and a key actuated lock arranged adjacent the tightening lever and adapted to prevent unauthorized manipulation thereof for the purpose set forth.

12. In a loose leaf book or binder of the type wherein the cover sections are united by flexible binding thongs or tapes on which one of the cover sections slides, the combination with a fastening thong connected to said binding thongs within the slideable cover section, of a tightening lever mounted within the cover sections, an outstanding finger piece carried by said lever and projecting through a segmental slot or opening

in the inner face of said cover section, a catch adapted to lock the tightening lever in different angular positions about its pivot, and thong gripping means pivotally connected to the tightening lever to detachably secure the fastening thong thereto, said gripping means having an outstanding lug or finger portion projecting through an aperture in the inner face of said cover section whereby the gripping means may be manipulated to grip or release the fastening thong for the purpose specified.

In testimony whereof I affix my signature. 30

F. B. A. KIRSTEN.
